(57) **CLAIM**

I claim the ornamental design for the lateral subluxation support, as shown and described.

DESCRIPTION

FIG. 1 is a perspective view of a lateral subluxation support shown on a left knee in assembled condition; the broken line showing of the knee being for illustrative purposes only and forming no part of the claimed design;

FIG. 2 is a front view thereof;

FIG. 3 is a rear view thereof;

FIG. 4 is a view thereof from one side;

FIG. 5 is a view thereof from the other side;

FIG. 6 is a view thereof from one end;

FIG. 7 is a view thereof from the other end; and,

FIG. 8 is a perspective view thereof, unassembled.

My new design for a right-handed, lateral subluxation support for the right knee is a mirror image of the design represented in FIGS. 1-8.
